J. E. STRIELMEIER.
SHEET METAL WHEEL CONSTRUCTION.
APPLICATION FILED NOV. 22, 1913.

Patented Mar. 11, 1919.

UNITED STATES PATENT OFFICE.

JOHN E. STRIETELMEIER, OF CINCINNATI, OHIO, ASSIGNOR TO THE IDEAL WHEEL COMPANY, OF CINCINNATI, OHIO, A CORPORATION OF OHIO.

SHEET-METAL WHEEL CONSTRUCTION.

1,296,873.

Specification of Letters Patent. Patented Mar. 11, 1919.

Application filed November 22, 1913. Serial No. 802,349.

To all whom it may concern:

Be it known that I, JOHN E. STRIETELMEIER, a citizen of the United States, and residing at Cincinnati, in the county of Hamilton and State of Ohio, have invented a new and Improved Sheet-Metal Wheel Construction, of which the following specification is a full disclosure.

This invention deals with a resilient wheel, and it proposes a special hub construction consisting of few compactly related elements efficiently supporting sheet metal spoke-elements, and it is also concerned with a rim-construction that will be light, simple and well-adapted to cooperate with the resilient spoke elements.

Other objects will be in part obvious from the annexed drawings and in part indicated in connection therewith by the following analysis of this invention.

This invention accordingly consists in the features of construction, combination of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the view, of which:

Figure 1 is a fragmentary side elevation of a resilient wheel embodying the features herein claimed, parts being broken away to show more clearly certain features of construction thereof. Fig. 2 is a section taken on the radial plane indicated by line 2—2 of Fig. 1, showing other features thereof, and Fig. 3 is a fragmentary perspective view of the hub-element showing the annular slotted rib for retaining the spokes as well as a portion of the spoke-spacer.

Referring to the drawings, A indicates a hub-element which will be annular in form and internally configurated to be suitably mounted in accordance with the necessities of use. This hub-member A in this instance provides an external peripheral seat 1 that here assumes a form having a uniform diameter from end to end and prefer-

ably as long axially as possible, so as to permit the mounting of wide spoke-elements. This periphery 1 constitutes a seat for a spoke-spacing member, as will be hereinafter described and it is provided with a flange-like annular portion 2 that rises or extends outwardly at one side of the seat 1. This part 2 has an annular rib 3 which preferably is V-shaped and extends laterally so as to overhang the seat 1, as shown. It is desirable that this rib be so located as to leave an annular portion 4 projecting radially beyond the rib 3, so as to conceal the edges of the spoke-elements up to the point of leaving the spoke-spacer. 70

The spoke-spacer is indicated by B, and it consists of an integral annular piece having a continuous base portion 5, which concentrically seats on the periphery 1 of the hub member, and which preferably is as wide as possible. In one of its annular sides this spoke-spacer has an annular groove 6 that has a form complementary to the rib 3, so as snugly to interfit with the same, and in its other annular side it has another annular groove 7 that similarly receives the rib of a retaining collar. At peripherally spaced intervals, a series of radial slots 8 are formed in the spoke-spacer B, which slots are preferably of such width as snugly to receive two flat-wise spoke-elements as shown by Fig. 1, and these slots are preferably sufficiently deep to leave room for considerable spoke material along the diagonal line 9 shown by Fig. 2, and the bottom edge 90 of the slots 8 may take a straight line, as indicated by 10.

A retaining collar C is mounted in adjustable relation with the hub-element A in a suitable manner, as by means of the screw-threads 11, and it is located at the outer end of the spoke-spacer B and provides an overhanging rib 12, which is contoured to interfit with the groove 7 in the side of the spoke-spacer, and which preferably has a shape 100 similar to the rib 3 of the hub-member.

The spokes preferred by this invention have a loop-like form, as shown by Fig. 1, and are composed of a forward and a rearward sheet metal spoke-element D and D' 105 curved in the plane of the wheel, and disposed edgewise thereto. These spoke-elements enter the slots 8 in pairs, and they have V-shaped notches 13 cut in their outward edges to engage the rib 12 of the 110

collar C and they may have similar notches in their other edges to engage the rib 3. To prevent turning of the parts with relation to the hub-member, it is proposed to 5 provide the rib 3 with suitable slots or notches in which one of the parts may interfit so as to be laterally restrained against movement, and in this instance, these notches are indicated by 14 and register 10 with the slots 8 so as to receive the spoke-element D, as appears more clearly by Fig. 2. In this instance the notches in the spoke-elements are in the form of a trapezoid. The inner edge of the spoke-element may 15 be spaced away from the bottom of the slot 8, as indicated by 15, so as to enable the spoke-elements to be supported against radial movement entirely by the ribs 3 and 12.

20 The rim F proposed by this invention preferably consists of a single channel iron 16 having its external periphery suitably contoured to receive a tire, and which is reinforced by an inner concentrically related 25 metal ring 17 having end flanges 18 bent concentrically to bear against the inner periphery of the ring 16 and welded to the same at the contacting points. This provides an annular space 19 within which may be 30 located at intervals bosses 20 for receiving the threaded ends of retaining bolts G. As shown by Fig. 1, this inner ring 17 will preferably be indented to form seats 21 for the spoke-elements, which in this instance terminate in hook-shaped end portions 22 which are arranged in a reverse relation, as shown 35 more clearly by the drawings.

A yoke-shaped retaining block E has a channel 23 extending longitudinally, which 40 receives the extremities 24 of the spoke elements, and on each side of this channel there are ribs 28 having a curved contour snugly interfitting within the pockets of the spring-elements, as shown. A bolt G passes through 45 a central radial aperture in the retaining block E and the hook-shaped ends of the spring-elements are cut away, as indicated by 26, Fig. 2, so as to enable this bolt to extend in operative connection with the boss 50 20, whereby it may be tightened up to draw the block E adjustably into binding relation with the spoke elements.

Without further elaboration, the foregoing will so fully reveal the gist of this in-

vention that others can by applying current 55 knowledge readily adapt it for various applications without omitting certain features that, from the standpoint of the prior art, fairly constitute essential characteristics of 60 the generic or specific aspects of this invention, and therefore such adaptations should and are intended to be comprehended within the meaning and range of equivalency of 65 the following claims.

Having thus revealed my invention, I 65 claim as new and desire to secure by Letters Patent of the United States:—

1. A resilient wheel of the nature disclosed combining a hub-member; a series of resilient sheet-metal spoke-elements emerging 70 from said hub-member and each terminating in a hook-shaped end-portion; a first sheet-metal flanged ring constituting a tire-retaining member; a second sheet-metal flanged ring concentric therewith and having its 75 flanges secured to the inner periphery of the first ring; an internal threaded boss located between said outer and inner rings; a series of spaced blocks at the inner periphery of the second ring, each having an integral rib-like portion interfitting within the pocket of 80 its associated hook-shaped spoke-portion, and a bolt extending radially to secure a corresponding block, said bolt having a screw-threaded engagement with said boss. 85

2. A resilient wheel of the nature disclosed combining an elongated yoke-block having an elongated central channel and elongated ribs at each side thereof having curved contours, a resilient flat spoke-element extending at one side of said block and terminating in a curved end-portion interfitting with the adjacent rib and having a bifurcated end, a counterpart spoke-element reversely arranged in similar relation with the other rib, a rim-member providing curved seats, and adjustable means for urging said block toward said rim-member to clamp said spoke-elements therebetween, said means being in nested relation with the bifurcations in said 90 spoke-elements. 100

In witness whereof, I hereunto subscribe my name, as attested by the two subscribing witnesses.

JOHN E. STRIETELMEIER.
